LUCIUS B. CLOGSTON, OF FAIR HAVEN, VERMONT.

IMPROVEMENT IN MACHINES FOR SAWING MARBLE.

Specification forming part of Letters Patent No. 154,320, dated August 25, 1874; application filed May 13, 1874.

To all whom it may concern:

Be it known that I, LUCIUS B. CLOGSTON, of Fair Haven, State of Vermont, have invented certain new and useful Improvements in Machines for Sawing Marble and other Stone; and I do hereby declare that the following is a description thereof, reference being had to the accompanying drawings (in two sheets) forming a part of this specification, in which—

Figure 1 represents a side elevation of the machine embodying the improvements in this invention. Fig. 2 is a plan of the same. Fig. 3 is a perspective view of the device for holding the saws to their work. Fig. 4 is an end view of the machine, illustrating the several parts of the invention. Fig. 5 is a perspective view of the feeding mechanism used with this machine on an enlarged scale. Fig. 6 is a sectional view of the holding-down device, illustrating its operation. Fig. 7 is a sectional view of a modification of the holding-down device.

My invention relates to certain improvements in machines for sawing stone, and consists in the employment of certain new combinations of devices with the usual frame and operating parts of the machine whereby the saws will be held down to their work; they will be rendered automatic, and the saws be more readily lowered or raised, all of which I will proceed to describe in reference to the drawings and letters of reference marked thereon, the same letters indicating like parts.

In the drawings, A A represent the usual posts acting as guides to the saw-frame, and supporting the upper structure. A' A' are the bearing-timbers of the frame supporting the usual windlass B carrying the drum B', and the shafts C C bearing the sheaves C' C'. D is the gang-saw frame suspended from above, and capable of being raised or lowered by the chains, wire cable, or rope D' passing from the windlass B over the sheaves C' C', and connecting with the traveling bars E, which is connected with the said saw-frame by the usual suspension-rods E' E'. The said saw-frame is operated by the pitman F, from a crank-wheel, F', in the usual manner.

All the above parts are old, and form no

part of this invention, but are used in connection with my improvements.

Heretofore the saws in the gang-frame were permitted to enter the stone by their abrasion of the same, arising from a reciprocating movement of the saws, attended by the pressing down of the same by the weight of the frame of the gang, which frame, when oscillating in a rapid manner, would rise or be thrown up at each extreme of the throw of the pitman, and thereby carry the saws above their intended cut; or the saws have been kept down to their work, and against such throw-up, by screw-threaded revolving-rods working into screw-threaded housings attached to the traveling bars at each end, in which, after a few days wear, there would be produced considerable backlash; or again, the saws have been held down by a pawl or dog, secured to the ends of the traveling bar, and working into rack-bars standing vertical with the guide-posts, which arrangement was defective because the teeth of the rack-bars would not correspond in most cases with the depth of the cut given at each stroke of the saws, growing out of the varying degrees of hardness in the stones operated with.

In my invention I use the smooth bars G, Figs. 1, 2, 3, 4, and 6, placed vertical and parallel with the guide-posts A A and each other, as shown, and supported at their ends from the brackets a a, Figs. 1 and 4. The ends of the traveling bars E E are provided with the housings G' G', secured firmly to the said traveling bar, and working with the vertical bars G, which they surround and act with as ways for the proper guiding of the said traveling bar in its descent. H H are friction-grippers, closing round the vertical ways G between the jaws of the housings G' G', and pivoted to the ends of the traveling bars, and at a point below the top edge of the gripper, and from the arm e, so as to be capable of a swinging movement from the lower side of the upper jaw of the housing to a point near to or below a plane with the point x of the pivoting of the said gripper, as shown in Figs. 3 and 6. Pivoted to the arms b b (preferably) of the housings is the bell-crank levers ee', one of which levers is placed beneath the gripper, while the other connects with a

draw-rod, *f*, connected with a hand-lever, *f'*, Figs. 4 and 6. The said lever *f'* operates simultaneously with each of the draw-rods *f*, to operate the bell-crank levers *e e'*, to throw the grippers *H H* up, as shown by full lines in Fig. 3 and dotted lines in Fig. 6, or to permit the fall of the said grippers to a position shown by full lines in Fig. 6 and dotted lines in Fig. 3. When the said grippers are thrown up the traveling-bar is capable of being moved vertically in either direction; but when the said grippers are cast down the said bar can only be moved downward, while all upward moving of the said bar is effectually prevented by the wedging operation of the guide-bar *G* with the housing *G'*, and the said grippers as they bind against the guide-bar, and key the housing from sliding upward on the same. By this part of my invention each fraction of an inch of the lowering of the traveling bar will be firmly held, so that when the swinging gang-frame *D* is being oscillated and moved at the lower point in the arc naturally described the grippers will hold the said frame down, (through the traveling bar *E* and suspension-rods *E''*), and force it to move in a plane with the said lowest point of the natural described arc, and thereby cause the saws to enter the stone without any tendency to throw up, as would be the case were the grippers not employed. When the lever *f'* is in the position shown in Fig. 3 by full lines the grippers will be thrown up, and in case a saw is broken or the gang of saws is to be replaced, the operator will permit the frame to be oscillated, and at the same time gradually raised, until the saws are elevated above the stone; but when the lever *f'* is moved to position shown by dotted lines the grippers will fall down and be made to wedge close with the ways *G*, and thereby prevent the saws from throwing up, and at the same time follow down with the traveling bar in a free manner.

I would not confine myself to any particular form of friction clutch or gripper to operate for wedging the vertical way *G* with the housings *G'*, as its form can be variously changed, and instead of it being made to clasp and encircle the said way, as in Figs. 3 and 6, it may be made to operate with one side of the way, and between the same and one side of one of the jaws of the housings, in which I would make it wedge-shaped and suspended from the arm *e* of the bell-crank lever *e e'*, as shown in Fig. 7, when the operation and results would be the same.

To properly feed down the saws to their work with the stone, and adapt the feed to the degree of hardness of the stone operated with most advantageously, I support, from proper brackets or bearings attached to the timber *A'*, the pulley *I* by the shaft *I'*, and connect the said pulley to the shaft *F²* or a band-wheel, Figs. 1 and 2, by a band, *g'*. The end of the said shaft *I'* is provided with a crank, *h*, which operates a draw-bar, *h'*, at-

tached to a slotted lever, *k*, pivoted to the shaft of the screw-gear *J*, Figs. 1 and 5, which lever is slotted in its loose end and carries a pawl, *k'*. The connecting end of the rod or draw-bar *h* may be variously set in the said slotted lever, so as to act with a greater or less number of the teeth in the ratchet-wheel *K*, attached to the shaft of the screw-gear *J*, which ratchet-wheel, when operated by the said slotted lever and pawl from the crank above, will give motion to the gear *L*, secured to the shaft *i*, Fig. 5, carrying the pinion *L'*, which operates with the gear *M*, secured to the drum *M'* or its shaft. The drum *M'* carries the main feed-chain *N*, which feeds off from the drum *M'* on the drum *B'* as the weight of the gang-saw frame *D*, with its saws, draws on the chain or wire cable *D'*, passing over the sheaves *C C'* from the windlass *B*, connected with the drum *B'*, unwinds. Placed intermediate between the drum *M* and the pinion *L*, and with the gear *L'* operating with the drum-gear *L*, is the clutch *O*, Fig. 5, secured to the shaft *i*, which clutch consists of a ratchet-wheel, *m*, secured to the said shaft, and a pawl, *n*, secured to the pinion and acting with the said ratchet-wheel by any suitable spring or equivalent, and may be thrown out of action when desired. The pinion *L* is loose on the shaft *i*, and is only carried with the said shaft when the said pawl is thrown in action with the ratchet-wheel *m* of the pinion *L*.

In machines for sawing stone it is often desirable when a saw breaks, or when a new gang is to be replaced, especially when the stone is partially sawed, to remove the saws immediately before the sand used with the saws sets around them. This can only be done by quickly raising them out of their grooves in the stones. In my invention I facilitate the operation of raising the saws from their grooves by the several parts of my invention coacting with the reciprocating movement of the same.

When it is desirable to elevate the gang-saw frame with its saws, I permit the driving-crank *F'* and its pitman *F* to operate in the usual manner, and by means of the hand-crank *Q*, turned in the proper direction, operate the pinion *P*, which operates the drum, gear *M*, which revolves the drum *M'* and winds up the feed-chain *N*, and revolves the drum *B'* with the windlass *B*, and thereby elevates the gang-frame *D* by means of the chains *D'* or their equivalents. When the saws have been replaced or the finished stone has been removed and a new stone substituted, I throw the pawl *n* out of

contact with the ratchet-wheel *m* of the pinion *L*, when the gang-frame will, by its own gravity, settle down to the stone, the several chains reeling off and on the several drums in their proper direction. The pawl *n* is then thrown into action with the ratchet *m* of the pinion *L*, and the operation of feeding down the saws to the stones will proceed. As before stated, the gripper *H*, when operating with the vertical ways *G*, will permit only a down movement of the saw-gang frame *D*. It is therefore necessary, before using the crank *Q* for hoisting the saws out from their grooves in the stone, to throw the lever *f* from a position shown by dotted lines to that shown by full lines in Fig. 3, so as to throw the said friction-grippers out of action with their ways, and thus permit a free sliding of the housing *G' G'* on the same, that the traveling bar *E*, connecting the said frame with the chains *D'* will be capable of being raised.

When the stone operated with is of such hardness as to necessitate a slow feed, the draw-rod *h'*, operated by the crank *h*, is to have its connection with the lever *k*, operating the pawl *k'* with the ratchet-wheel *K*, placed toward the end of the slot in the said lever, when the screw-gear *J* will be made to operate slower with its gear to effect a slower feeding off of the main chain from the drum *M*, and consequently a less feed down of the saws to the stone. When the speed of the feed is to be increased, the connecting end of the said draw-rod is to be moved nearer to the said pawl. When the hardness of the stone varies the operator, without stopping the

motion of the machine, will variously shift the connection of the said draw-rod with the slotted lever, as may be required by the degree of hardness of the stone as it may vary.

By the improvements in this invention the feed of the saws can be adapted to the degree of the hardness of the stone, the saws may be raised up from their grooves or lowered to their work in a ready and easy manner, while each fraction of an inch of the fall of the gang-saw frame will be held down in a firm manner without the least liability of a backlash or throwing up of the saws from the lower line of the grooves cut. The operations of the several parts are positive, and the several parts are in themselves simple and not liable to excessive wear.

Having described my invention, what I claim, and desire to secure by Letters Patent, is—

1. In stone-sawing machines, employing a suspended saw-frame supported from a suspended traveling bar by stiff suspension-rods, the combination of the friction-griper *H H*, with the vertical ways or bars *G G* and the housings *G' G'* attached to the said traveling bar, substantially as set forth.
2. In combination with the friction-griper *H*, the bell-crank levers *e e'*, draw-bar *f*, and hand-lever *f'*, substantially as set forth.

LUCIUS B. CLOGSTON.
